[57] CLAIM

The ornamental design for signpost with profiled configuration, substantially as shown and described.

DESCRIPTION

FIG. 1 is a perspective view of a signpost with profiled configuration showing my new design;

FIG. 2 is an end elevation view thereof, shown with a signpost bracket and sign in broken lines for illustrative purposes only.

The signpost has been shown fragmentarily in FIG. 1 to indicate indeterminate length.

FIG. 1

FIG. 2
